UNITED STATES PATENT OFFICE.

ALFRED F. LANCE, OF CHICAGO, ILLINOIS.

SPRING STRUCTURE.

1,352,612.

Specification of Letters Patent. Patented Sept. 14, 1920.

Application filed October 11, 1918. Serial No. 257,808.

To all whom it may concern:

Be it known that I, ALFRED F. LANCE, a citizen of the United States, residing at Chicago, in the county of Cook and State of Illinois, have invented certain new and useful Improvements in Spring Structures, of which the following is a specification.

My invention relates to spring structures to resiliently support the unattached end or side of the hinged top, or cover of a box seat.

One of the objects of my invention is to provide a self-contained spring structure that may quickly be attached to a box and as conveniently be removed therefrom without requiring any change or modification of the box or its cover.

Locomotive engineers suffer greatly from the relative rigidity of the seat provided for them in their engine cabs, from the constant and harsh vibration caused by impact of the moving locomotive over the underlying rails. In all such cabs an ordinary box is designed to contain the engineer's tools and working equipment and affords the only seat available for him. The cover for such boxes is usually hinged at one end, or side, and it is the object of my invention to provide springs to yieldingly support the free movable edge of the hinged cover whereby to absorb the incipient vibrations that would otherwise be imparted to the person resting on the box cover.

The spring structures become the personal property of the engineer operating the particular engine and therefore it is highly desirable that the structure may be quickly taken from its position, under the box cover, when the engineer changes locomotives, and it is further useful to have a device of this character without loose or detached parts.

In the accompanying drawings, illustrating one form of my invention—

Figure 1 shows the upper or plan view of a box with the cover removed.

Fig. 2 is a central vertical section of a box seat.

Fig. 3 is an enlarged central section through the spring structure; and

Fig. 4 is a transverse section taken on line 4—4 of Fig. 3.

In all the views the same reference characters are employed to indicate similar parts.

5 is a box and 6 is a cover hinged thereto, as at 7. 8 may be a cushion on the top of

the box to afford a relatively soft seat for the engineer.

The spring structure consists of a housing 9 in general cylindrical form, being cut away on each side, as at 10, to reduce its weight and provided with a laterally and downwardly extending hook 11, to extend over the upper edge of the box to support the structure thereon. A spring 12, extending above the upper edge of the structure 9, is secured at the bottom by a pin 13, which passes entirely through the side walls of the cylindrical portion and overlies one or two of the bottom convolutions of the spring, to hold it in place. The pin is provided with a pointed head 14 to engage the side of the box to prevent lateral movement of the structure when in place.

The device is exceedingly simple and is highly efficient and satisfactory in operation for the purpose intended. To place a pair of the spring structures in proper position on the box, with reference to the top, it is only necessary to place the hooks 11 over the top edge of the box, as shown in Figs. 1 and 2, and to permit the box cover or top to rest upon the upper ends of the springs 12. It is equally convenient to remove the structures from the box simply by raising the cover and lifting the devices from their positions.

The spring 12 is made small, with reference to the inside of the cylindrical portion 9, so as not to contact the metal part of the support, thereby to create friction and to make a noise.

Having described my invention, what I claim is:

A spring support for a box cover comprising a cylindrical housing for containing a helical spring, having an outwardly and downwardly extending hook at its top end to overlie the top edge of the box; a pin extending through the cylinder engaging the lower portion of the spring to hold it in place, and having a part projecting therefrom under the hook to engage the side of the box; and an open helical spring in said housing in contact with the bottom thereof, and held in place by said pin, and extending above the housing for engagement with the cover.

In testimony whereof I hereunto subscribe my name.

ALFRED F. LANCE.
